APPARATUS FOR FEEDING GRANULAR MATERIAL INTO A FLUID STREAM

Filed Dec. 29, 1945

UNITED STATES PATENT OFFICE

2,420,388

APPARATUS FOR FEEDING GRANULAR MATERIAL INTO A FLUID STREAM

William A. Thomas, Pittsburgh, Pa., assignor to Blaw-Knox Company, Pittsburgh, Pa., a corporation of New Jersey

Application December 29, 1945, Serial No. 637,819

11 Claims. (Cl. 302—25)

1

This invention relates to apparatus for feeding granular material and, in particular, to a feeder adapted to introduce material into a confined space against a predetermined back pressure existing therein.

In many industrial operations, particles of solid material are conveyed through a pipe by entrainment in a gas stream flowing therethrough. It is frequently desirable to introduce solid particles into such a conveying stream against the static pressure of the gas in the pipe. Gas-jet injectors have been used for this purpose. Usually, the motive fluid for the injector is the same as that circulating through the pipe although this is not necessarily so. If the solid material entering the conveying stream is delivered without being controlled, an excess of material will usually be drawn into the conveying stream and an objectionable loud whistling noise is produced.

While gas-jet injectors serve satisfactorily for introducing solid materials into a gas stream against the pressure thereof, under favorable conditions, certain materials have a tendency to build up accumulations in the form of a crust at the entrance into the Venturi tube usually incorporated in the injector. These accumulations obstruct the Venturi tube and tend to close off the passage therethrough, eventually rendering the injector inoperative. This is aggravated if the material being fed has a substantial moisture content.

I have invented a novel form of means for feeding granular material into a confined space against back pressure. My invention embodies a gas-jet injector and means for periodically scraping the entrance end of the Venturi tube thereof to prevent the accumulation of solid material thereon and to scoop up any particles which may be temporarily deposited thereon and return them to the gas stream through the injector. In a preferred embodiment, my invention comprises an injector including the usual Venturi tube and nozzle for delivering a jet of motive fluid therethrough. A feed box delivers material to be fed at the entrance end of the Venturi tube and a scraper means mounted for rotation about a fixed axis extends into the entrance end of the Venturi tube for wiping or sweeping movement therearound. Conveniently, the scraper means has the form of a flat blade and is mounted for rotation

2

about the common axis of the gas nozzle and Venturi tube. The invention also contemplates suitable driving means for rotating the scraper blade.

5 A complete understanding of the invention may be obtained from the following detailed description thereof which refers to the accompanying drawing illustrating a present preferred embodiment. In the drawings,

10 Figure 1 is a sectional view taken along the central vertical plane, with parts in elevation; and

Figure 2 is a transverse section taken along the plane of line II—II of Figure 1.

15 Referring now in detail to the drawings, the apparatus of my invention comprises an injector 10 including a base plate 11, a feed box 12 and a barrel 13. The feed box is composed of upper and lower plates 14 and 15, a rear plate 15a and side plates 16. One of the side plates preferably has a tight fitting clean-out door 16' hinged thereto adjacent the base plate 11. The material to be fed is delivered to the upper end of the box 12 by any suitable means such as a laterally extending screw conveyor 17. The upper end of the box 12 is closed by a plate 18 thereon having an air inlet fitted with a silencer in the form of a conventional air filter 19.

20 A flange plate 20 is welded to the forward edges of the upper plate 14 and the side plates 16 of the feed box and the base plate 11. A barrel 21 in the form of a cylinder or pipe 22 having terminal flanges 23 and 24 welded thereon extends forwardly from the plate 20. A Venturi tube 25 is 25 removably disposed in the barrel, the forward end thereof seating against the flange 24 and the rear end thereof having a shoulder 26 accommodated in a recess formed by counterbores in the adjacent faces of the plate 20 and flange 23. The flange 23 is secured to the plate 20 by screws 27 with sealing gaskets between their mating surfaces and also 30 between them and the opposite faces of the shoulder 26 of the Venturi tube 25. The plate 20 has a conical central opening 20a, forming a continuation of the entrance to the throat of the tube 25. The flange plate 20 may serve for mounting the entire feeding mechanism on a suitable support and the flange 24 may be secured to the pipe, duct or other passage or container to which the 35 material is to be fed.

The feed box 12 and the barrel 21 define a gas-tight passage for the flow of granular material under the impact of a gas jet. A nozzle 28 for discharging such jet is disposed coaxially of the Venturi tube 25, being mounted at the end of a gas-supply pipe 29 extending rearwardly therefrom. The pipe 29 extends through a gear box 30 defined by the base plate 11, the rear plate 15a of the feed box, a side plate 31, a top plate 32 and an end plate 33. The pipe is connected to any suitable source of motive fluid under pressure, e. g., superheated steam. The rear end of the pipe is threaded to accommodate nuts 34. By turning these nuts, the pipe 29 may be adjusted toward and from the entrance to the Venturi tube.

A sleeve bearing 35 is positioned in the gear box 30 coaxial with the pipe 29, being mounted on the rear wall 15a of the feed box by screws 36. A hollow shaft 37 is journaled in the bearing 35 and projects forwardly into the feed box 12. The pipe 29 extends through this shaft. Scraping means in the form of a flat plate or blade 38 is mounted on the shaft 37 by means of clamping yokes 39. The forward end of the plate extends into the entrance end of the Venturi tube 25 and is shaped to conform thereto as indicated at 38a. It will be apparent that, on rotation of the shaft 37, the blade rotates bodily about the common axis of the pipe 29, nozzle 28 and Venturi tube 25, and serves to wipe or scrape off any granular material which may have accumulated in the entrance end of the tube.

A laterally extending shaft 40 is journaled in a bearing carried by the side wall 31 of the gear box and is driven by any suitable means such as a pulley 41 and belt 42. A bevel pinion 43 on the shaft 40 meshes with a bevel gear 44 secured to the rear end of the hollow shaft 37. The shaft 40 may be driven by a separate motor or from the shaft of the conveyor 17. In any event, the drive should be such that the shaft 37 is rotated at a speed of about eight to ten revolutions per minute.

It will be apparent from the foregoing that the invention provides injector means for feeding granular material to a confined space against a back pressure existing therein, having provision for preventing the building up of accumulations of material at the entrance of the Venturi tube of the feeding injector which might obstruct the latter or eventually completely clog it. The slow rotation of the scraper blade not only removes any accumulations which might tend to stick to the entrance to the Venturi tube but also stirs up material in the body of the feed box adjacent thereto and subjects it to the inspiriting effect of the gas jet. The invention is particularly adapted for delivering coal to an impact grinder wherein the coal particles as fed are so actuated by steam-jet injectors as to cause fragmentation thereof by collision. A particular advantage of the invention in this type of installation is that it makes possible the handling of coal having a moisture content as high as 10%. Attempts to feed this type of coal into a pulverizer by an ordinary injector have resulted in the building up of substantial deposits of material at the entrance to the Venturi tube which obstruct the proper functioning thereof if they do no close it altogether. A similar condition is encountered in feeding other materials such as sulphur, clay, limestone or the like if a substantial amount of moisture is present therein. The invention thus makes it possible to burn certain grades of coal in a pul-

verized fuel burner which could not be pulverized by other means, such as a ball mill because of the tendency to form a paste which clogs up the mill and defies mechanical handling.

5 Although I have illustrated and described but a preferred embodiment of the invention, it will be recognized that changes in the details of construction disclosed may be made without departing from the spirit of the invention or the scope 10 of the appended claims.

I claim:

1. In an apparatus for feeding granular material into a fluid stream, the combination with a fluid-jet injector including a nozzle and a Venturi tube, of a scraper blade extending generally axially into the entrance of said tube, and means 15 mounting said blade for rotation about a fixed axis.

2. In an apparatus for feeding granular material into a fluid stream, the combination with a 20 fluid-jet injector including a nozzle and a Venturi tube, of a scraper blade extending generally axially into the entrance of said tube, and means mounting said blade for rotation about the axis 25 of said nozzle.

3. In an apparatus for feeding granular material into a fluid stream, the combination with a fluid-jet injector including a nozzle and a Venturi tube, of a scraper blade extending generally 30 axially into the entrance of said tube, and means rotatable about said nozzle for supporting said blade.

4. In an apparatus for feeding granular material into a fluid stream, the combination with a fluid-jet injector including a nozzle and a Venturi tube, and a feed box adapted to deliver material to the entrance of said tube, of a sleeve rotatable on said nozzle, and a scraper blade mounted on 35 said sleeve and extending into said entrance.

5. In an apparatus for feeding granular material into a fluid stream, the combination with a fluid-jet injector including a nozzle and a Venturi tube, of rotary scraper means for preventing 40 accumulation of said material at the entrance to said tube, and means for driving said scraper means.

6. In an apparatus for feeding granular material into a fluid stream, the combination with a fluid-jet injector including a nozzle and a Venturi tube, of a scraper blade extending generally 45 axially into the entrance of said tube, a sleeve rotatable on said nozzle, said blade being mounted on said sleeve, and means for driving said sleeve.

7. In an apparatus for feeding granular material into a fluid stream including a Venturi tube, a nozzle discharging into the tube coaxially thereof, and means for feeding granular material 55 into the entrance of said tube, the improvement comprising scraper means extending into said tube, means mounting said scraper means for rotation, and means for driving said mounting means.

8. In an apparatus for feeding granular material into a fluid stream including a Venturi tube, a nozzle discharging into the tube coaxially 60 thereof, and means for feeding granular material into the entrance of said tube, the improvement comprising a sleeve rotatable about said nozzle, a scraper blade mounted on said sleeve and extending into the entrance of said tube, and means 65 for driving said sleeve.

9. In an apparatus for feeding granular material into a fluid stream including a Venturi tube, a nozzle discharging into the tube coaxially 70 thereof, and means for feeding granular mate-

rial into the entrance of said tube, the improvement comprising a bearing coaxial with said nozzle and spaced rearwardly of said tube, a sleeve journaled in said bearing, a scraper blade mounted on said sleeve and extending into the entrance of said tube, said nozzle extending through said sleeve, and means for driving said sleeve.

10. The apparatus defined by claim 9 characterized by said driving means including bevel gears.

11. Feeding apparatus for granular material comprising a barrel, a Venturi tube removably disposed therein, a nozzle coaxial with said tube, a feed box adapted to deliver material to said tube, and means mounted for rotation about said

nozzle adapted to scrape accumulations of material from the entrance to said tube.
